UNITED STATES PATENT OFFICE.

OTTO ELIAS, OF ROCHESTER, PENNSYLVANIA.

PLANE.

1,387,969.

Specification of Letters Patent. Patented Aug. 16, 1921.

Application filed December 27, 1920. Serial No. 433,242.

To all whom it may concern:

Be it known that I, OTTO ELIAS, a citizen of the United States, and resident of Rochester, in the county of Beaver and State of 5 Pennsylvania, have invented certain new and useful Improvements in Planes, of which the following is a specification.

This invention relates to planes, and more particularly to hand planes for cutting 10 grooves, having beveled side walls, in one operation, and has for one of its objects the provision of such a plane that will have a guide member adapted to travel in a previously formed groove, thereby guiding the 15 plane and spacing the succeeding grooves an equal distance from the preceding groove.

Another object is to provide said guide member with a spring mounting so that it will readily fit in grooves of varying depths.

20 Another object is to so position the bits of the plane that they will have the most efficient cutting angles, and will cut evenly and smoothly.

Other objects and advantages will be 25 readily apparent from the following specification and claims and will be illustrated in the accompanying drawings, in which:—

Figure 1 is a side elevation of a plane embodying the novel features of this invention.

30 Fig. 2 is a top plan thereof.

Fig. 3 is a bottom plan thereof.

Fig. 4 is a side elevation taken opposite to that of Fig. 1, and partly broken away to show the guide mountings.

35 Fig. 5 is a sectional end elevation on the line V—V of Fig. 2.

Fig. 6 is a perspective view of a plate pattern having a grooved surface, the grooves being such as are formed by the plane of

40 Figs. 1 to 5.

Referring particularly to the drawings, the numeral 2 designates the body portion of the plane, which may be made of wood or any other desired material, and is provided 45 with a hand grip 3 at its rear end, and a knob 4 adjacent its forward end, adapted to be gripped by the operator to guide and steady the plane.

A substantially V-shaped longitudinal projection or rib 5 is formed on the bottom face of the body portion 2 and adapted to ride in the groove being cut.

One side of said body portion 2 is cut away, forming an outlet 6 for the cuttings 55 or chips formed by the bits in cutting a groove.

Three bits are arranged in the body portion for cutting a V-shaped groove, and have their lower ends projecting through the outlet portion 6. Two of said bits, 8 and 9, respectively, extend upward and outwardly at opposite angles in suitable recesses in said body portion, and are adjustably secured in position by wedge members 10 and 11 respectively. The bits 8 and 9 are provided 60 with knife-like lower ends adapted to cut the beveled sides of a groove. The third blade 15 extends rearwardly on an angle in a suitable recess, and is set so that its cutting edge extends at an angle to the transverse 65 plane of the body portion 2 so that a lead cut is first made as the plane advances on the work and increases as the plane is advanced until the whole cutting edge of the 70 bit is engaged.

The blade 15 is adjustably held in position in its recess by a wedge member 16 in the same manner as the bits 8 and 9.

A longitudinal slot 17 is formed adjacent one side of the body portion 2 and an adjustable spring tensioned guide bar 18 is mounted therein. The guide bar 18 has a pair of guide pins 19 mounted in its upper face, which is cut away around each pin forming a seat 20. The upper face of the 85 slot 17 is correspondingly recessed, forming seats 21 and helical springs 24, mounted around the pins 19, have their ends mounted in the respective seats 20 and 21, and tend to normally press or force the guide bar 18 90 outwardly. The guide bar 18 is held in the slot 17 and limited in its movement by screws or pins 25 which pass through slots or guide ways 26 in the bar and are secured in the body of the plane.

The guide bar 18 has its lower longitudinal edges beveled as at 29, so that it will snugly fit within a groove cut by the blades 8, 9 and 15. The forward end of the guide bar 18 projects a considerable distance beyond the body portion 2 to facilitate its insertion in a previously formed groove.

In Fig. 6 a plate pattern 30 is shown, which is of a well known design used in making cast metal floor plates. The pattern 105 30 is provided with a plurality of longitudinal and transverse grooves 3, having beveled side faces.

It will be readily seen that in cutting a plurality of parallel grooves, such as are 110 shown in the plate 30, a plane constructed in accordance with this invention will greatly

facilitate the work. In using a plane constructed in accordance with this invention, it is only necessary to locate the first groove of each group, and to then insert the guide 5 bar in the previously formed groove in order to locate each succeeding groove of the group. Also the arrangement of the bits 8, 9 and 15 is such that the bevel will be cut on the side faces of the groove in the same operation that forms the bottom and cuts out 10 the groove, thus doing in one operation, what has usually necessitated two or more operations.

While only one embodiment of my invention is shown and described, it will be understood that it is only illustrative, and that I do not wish to be limited thereto since various changes in design and minor details of construction may be made without departing from the spirit and scope of my invention as defined in the appended claims.

I claim:—

1. A plane for forming grooves in a work piece, comprising a body portion, at least 25 one cutting bit mounted in said body portion having its cutting end projecting through the bottom face of said body portion, and a guide rib resiliently mounted for vertical movement in a slot in the bottom face of 30 said body portion, said guide rib being spaced to one side of said bit, and being adapted to fit in a previously formed groove, thereby guiding said plane to equally space each succeeding groove.

2. A plane for forming grooves in a work 35 piece, comprising a body portion, at least one cutting bit mounted in said body portion having its cutting end projecting through the bottom face of said body portion, a guide rib projecting from the bottom face of and 40 formed integral with said body portion and adapted to ride in the groove being cut, and a second guide rib spaced to the one side of said first named rib, said second named rib being mounted for vertical movement in a 45 slot formed in the bottom face of said body portion, and being adapted to ride in a previously formed groove to guide said plane and equally space each succeeding groove.

3. A plane comprising a body portion, 50 three bits adjustably secured in said body portion adapted to cut a groove having a flat bottom and outwardly flaring side wall portions, a guide rib formed integral with the bottom wall of said body portion on a 55 line with said bits and adapted to travel in the groove being cut, and a second guide rib resiliently mounted for vertical movement in a slot in said body portion, said last named guide member having its lower side 60 edges beveled, and being adapted to fit in a previously formed groove, thereby guiding said plane to equally space each succeeding groove.

In testimony whereof, I have hereunto 65 signed my name.

OTTO ELIAS.
